WIRE REEL

John Edward Whitaker, West Monroe, La.

Application December 21, 1938, Serial No. 247,090

6 Claims. (Cl. 242—94)

The device forming the subject matter of this application is a reel for carrying wire. One object of the invention is to improve the construction of the body of the reel, another object of the invention is to improve the construction of the spool of the reel, and another object of the invention is to improve the cover for the spool, so that these parts may cooperate properly, in use. A further object of the invention is to provide novel means for applying braking pressure to the spool, releasably, and under the control of the wire which is being drawn off the spool.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Fig. 1 shows, in top plan, a reel constructed in accordance with the invention, parts being broken away;

Fig. 2 is an elevation; Fig. 3 is a section on the line 3—3 of Fig. 1; Fig. 4 is a section on the line 4—4 of Fig. 1; Fig. 5 is a section on the line 5—5 of Fig. 3; Fig. 6 is a section on the line 6—6 of Fig. 1; Fig. 7 is a section on the line 7—7 of Fig. 1.

The device forming the subject matter of this application preferably is made of metal throughout. Angle iron construction can be used wherever desired.

The device forming the subject matter of this application comprises a body 1. The body 1 includes a bottom ring 2 and a top ring 3. The bottom ring 2 and the top ring 3 are connected by posts 4, preferably located about 90 degrees apart. Spokes 5 extend inwardly from the lower ends of the posts 4 and are secured to the bottom ring 2.

Where the spokes 5 intersect, at the axis of the body 1, they are secured to a foot 6 on the lower end of a hollow spindle 7. An anti-friction bearing 8 surrounds the lower end of the spindle 7 and is supported on the foot 6. Brackets 9 are secured to the outer portions of the spokes 5. Rollers 10 are journaled on the brackets 9 for rotation about axes at right angles to the axis of the spindle 7. Guards, in the form of bell crank levers 11, are fulcrumed at 12 on the posts 4. The inwardly extended arms of the bell crank levers 11 are heavier than the upwardly extended arms thereof, and, therefore, the upwardly ex-

tended arms of the bell crank levers tend to swing inwardly.

The numeral 14 marks a brake, extended circumferentially of the body 1. The brake 14 includes an end bar 15. The end bar 15 is connected by hinges 16 to one of the posts 4 of the body 1. The hinges 16 have a common hinge pin, about which is disposed a coiled spring 17. The coiled spring 17 engages the aforesaid post 4 and the end bar 15 of the brake 14, and tends to swing the brake inwardly. Any supplementing means (not shown) may be employed for swinging the brake 14 inwardly.

The brake 14 includes a U-shaped frame 18 secured to the end bar 15. A carrier plate 19 is attached to the upper and lower members of the frame 18, and is disposed near the end bar 15. A brake shoe 20 is secured at 21 to the inner surface of the carrier plate 19. Guides 22 are secured to the carrier plate 19 and to the upper and lower members of the frame 18. A latch bar 23 is mounted for reciprocation in the guides 22, in contact with one edge of the carrier plate 19. Lateral fingers 24 on the latch bar 23 limit its longitudinal movement in the guides 22. The latch bar 23 is held by gravity in its lower position. A stop strip 25 is fixed on the upper and lower members of the frame 18. The stop strip 25 has an inwardly offset upper end 26. A transverse roller 27 is mounted on the upper and lower members of the frame 18 for rotation, and is disposed near to the free end of the brake 14. A longitudinal, outwardly inclined roller 28 is mounted to turn on the frame 18, at the free end of the frame. The roller 28 extends into close relation to the roller 27, but the rotation of neither roller is impeded by the presence of the other roller.

The device includes a spool 29. The spool 29 embodies a ring 30. Spokes 31 extend inwardly from the ring 30 and are secured to a tubular hub 32. The hub 32 is mounted to turn on the spindle 7 of the body 1. The hub 32 has an outwardly extended, depending skirt 33. The skirt 33 rests on the anti-friction bearing 8 of the body 1 and extends about the bearing. The bearing 8, obviously, facilitates the rotation of the spool 29.

The ring 30 of the spool 29 is supported on the rollers 10 of the body 1, in the space defined by the posts 4. The upright arms of the bell crank levers 11 press against the ring 30 of the spool 29. The function of the bell crank levers or guards 11 is to prevent the wire on the spool 29 from getting beyond the edge of the ring 30, and moving downwardly between the posts 4, fouling and interfering with the rotation of the spool 29 thus being prevented. The offset upper end 26 of the stop strip 25 on the brake 14 is located inside the ring 30 of the body 1. The

function of the stop strip 25 is to limit the outward swinging movement of the brake 14 after the latch bar 23 has been raised from the position of Fig. 6 enough so that the lower end of the latch bar can clear the ring 2. The shoe 20 of the brake 14 bears against the ring 30 of the spool 29. The lower end of the latch bar 23 normally is disposed inside the bottom ring 2 of the body 1. It is possible, however, to raise the latch bar 23, swing the brake 14 outwardly on its hinges 16, and push down the latch bar 23 until it is outside the bottom ring 2 of the body 1. In this way, the brake shoe 20 is held out of contact with the ring 30 of the spool 29, and the spool can turn freely.

Standards 34 are disposed above the spokes 31 of the spool 29 and form a core about which wire may be wound. The standards 34 have inwardly extended feet 35 held by yokes 36 on the spokes 31, it being possible to shift the standards 34 in and out, to accommodate coils of wire of different diameters and to centralize the coil with respect to a vertical axis represented by the spindle 7 of the body 1. After the standards 34 have been adjusted in or out, they can be held in adjusted positions, by means of a holding device, such as a set screw 38, adapted to engage one of the spokes 31, the set screw being threaded into the yoke 36, and into a nut 37 secured in the yoke. All of the standards 34 can be adjusted in and out, in the manner specified.

A socket 39 of tubular form, is secured to one of the standards 34, and is adapted to receive a removable handle (not shown) whereby the spool 29 can be turned readily. In order to hold down the wire about the standards 34 of the spool 29, there is provided a cover 40, including a ring 41 connected by spokes 42 to a tubular hub 43, adapted to rest at its lower end on the spokes 31 of the spool 29. The hub 43 slides on the hub 32 of the spool 29 and is heavy enough so that it can follow the wire down, as the wire is taken off the spool, the coil of wire being held against jumping upwardly, out of place.

Although Fig. 1 is a top plan, it may be considered, at this place, as a side elevation. If the operator wishes to roll the device along the floor, in the position of Fig. 1, this can be done without injury to the roller 28 or the hinges 16, because the rings 2 and 3 of the body 1 are supplied with outwardly convexed tracks, connected to the said rings, on opposite sides of the roller 28 and the hinges 16, the tracks being designated by the numeral 50.

If desired, an annular cap 51 may be placed about the spindle 7, at the upper end of the spool hub 32, the cap 51 being held in place, detachably, by a cotter pin 52, or otherwise.

The wire is led off the spool 29, between the roller 27 and the end bar of the frame 18, and over the top of the roller 28. When the wire is pulled upon, to remove it from the spool 29, the brake 14 is swung outwardly on the hinges 16, the brake shoe 20 no longer has contact with the ring 30 of the reel 29, and the reel can turn freely; but as soon as the wire is slackened away, the spring 17 swings the brake 14 inwardly, and the shoe 20 comes into contact with the ring 30 of the spool 29, as shown in Fig. 1. If the brake 14 were permitted to swing too far outwardly, for example and in an extreme instance, until it occupies a position at right angles to the one shown in Fig. 1, the wire would be bent sharply

across the parts adjacent to the hinged end of the brake and would not pay out freely. The function of the stop bar 25 thus is made manifest. The device is simple and inexpensive in construction, but will be found thoroughly advantageous and practical for the ends in view. 5

Having thus described the invention, what is claimed is:

1. In a device of the class described, a body, a wire receiving spool journaled in the body, a 10 brake hinged to the body, spring means for actuating the brake to cause it to engage the spool, and a latch movable on the brake, the latch cooperating with the body, to hold the brake out of engagement with the spool. 15

2. In a device of the class described, a body, a wire receiving spool journaled in the body, a 20 brake hinged to the body, spring means for actuating the brake to cause it to engage the spool, a stop carried by the brake and engageable with the body, to limit the outward swinging movement of the brake with respect to the spool, and a movable latch on the brake and cooperating with the body to hold the brake in its outwardly-swung position. 25

3. In a device of the class described, a body, a wire receiving spool journaled in the body for rotation about a vertical axis, and bell-crank guards pivotally mounted on the body and including upright arms engaging the periphery of the spool, 30 to prevent the wire on the spool from moving downwardly about the periphery of the spool, the guards comprising inwardly-extended arms prolonged below the spool and constituting means for maintaining the upright arms engaged 35 with the spool.

4. In a device for carrying wire, a body having an upright spindle, a spool comprising a core about which wire may be wound, the spool being provided with a tubular hub journaled on the 40 spindle and disposed centrally with respect to the core, and a spool cover surrounding the core, the cover having a hub mounted removably on the hub of the spool, and vertically slidably thereon to permit the cover to rest on the wire wound 45 about the core and to follow the wire down, as the wire is unwound from the core.

5. In a device of the class described, an approximately circular body, a wire receiving spool journaled on the body, a brake, a hinge connecting the brake with the body, means for causing the brake to engage the spool, an outstanding member on the brake, along which the wire passes as it is drawn from the spool, and an outwardly convexed track secured to the body on 50 opposite sides of the hinge and said member, and extended outwardly therebeyond, whereby when the body is rolled on its periphery, the hinge and said member will be protected. 55

6. In a device for carrying wire, a body, a 60 spool journaled on the body, a brake hinged at one end to the body, means for causing the brake to engage the spool, a first roller disposed transversely of the brake and journaled thereon, adjacent to the opposite end of the brake, and a 65 second roller disposed longitudinally of the brake and supported for rotation on said opposite end of the brake, the second roller slanting outwardly with respect to the brake and the first roller and overlapping the first roller, in close relation thereto, the rollers constituting wire guiding elements. 70

JOHN EDWARD WHITAKER.
